DENTAL FLOSS HOLDER

Filed Nov. 24, 1939

UNITED STATES PATENT OFFICE

2,217,917

DENTAL FLOSS HOLDER

Harold W. Munro, Providence, R. I.

Application November 24, 1939, Serial No. 305,963

10 Claims. (Cl. 132—92)

This invention relates to a dental floss holder and has for one of its objects to provide a holder which in use will provide an unobstructed view of the area of the mouth where cleansing between the teeth is performed, all by reason of parts on the holder and without the necessity of using a second hand or separate device for holding the mouth open.

Another object of the invention is to provide a dental floss holder which will enable the mouth to be held open and lips and inner cheek held out of the way for viewing the cleaning action and will make it unnecessary to place the fingers in the mouth to accomplish this result.

15 A further object of the invention is to provide a broad side view of the base of the teeth at the area being cleansed.

Another object of the invention is to provide for a view of the teeth without holding the mouth open to a large extent, but rather by pushing back the lips without unduly stretching them to afford such viewing.

20 Another object of the invention is to prevent pinching of the lip by a sawing action of the floss as it is drawn in and out between the teeth.

Another object of the invention is to provide a convenient holder for a supply of the dental floss and the maintaining of this floss in a housed, packaged position until it is to be used.

25 Another object of the invention is to provide a convenient location for mounting of various desirable parts, such, for instance, as a cutter, clamping devices, and devices indicating how the floss is to be woven into fixed position.

30 Another object of the invention is to provide a movable arm provided with a convenient clamping device by means of which the movable arm which mounts one end of the bridging portion of the floss may be swung to tighten the floss, without it being necessary to provide additional means to draw the floss across the arm.

35 With these and other objects in view, the invention consists of certain novel features of construction, as will be more fully described, and particularly pointed out in the appended claims.

40 In the accompanying drawing:

Fig. 1 is a perspective view of the device with the floss arranged in working position;
 45 Fig. 2 is a section on line 2—2 of Fig. 1;
 Fig. 3 is a section on line 3—3 of Fig. 1;
 Fig. 4 is a section on line 4—4 of Fig. 1;
 Fig. 5 is a perspective view of the pivotally mounted arm with the clamping section of the
 50 post omitted;

Fig. 6 illustrates a side elevation of the device as inserted into the mouth of the user;

Fig. 7 is a view similar to Fig. 6, but showing the device in inverted position in the mouth of the user;

Fig. 8 is a side elevation of the device in relation to the mouth in a still different position; and

Fig. 9 is a side elevation as a modified form of the device.

In the use of dental floss it is convenient to provide a holder which will maintain the floss tight so that the same may be inserted between the teeth for removing any foreign matter between the teeth by a sawing action. A fixed, short U-shaped device for performing such action is sometimes used, but when such a device is used, if one wishes to view the area being operated upon, it is necessary to hold back the lips with another hand. A bow device is also sometimes used for holding the floss where the floss is extended over a substantial length. These devices also require a second hand to be used to hold the lip back and if the lip is not held back in the use of such a bow device, frequently the lip may become pinched by the sawing action of the floss between the teeth.

In order to avoid these difficulties and also to provide a viewing action in a bow structure, I have provided a guard which will engage the lip or any portion of the face about the mouth and prevent the same from crowding in about the bow and will also prevent the lip from being pinched by the action of the holder, and the following is a more detailed description of the present embodiment of this invention, illustrating these preferred means by which these advantageous results may be accomplished:

With reference to the drawing, 10 designates the body portion, the shape of which may be better illustrated in the drawing than described. This body portion is arched as at 11 with the handle portion 12 extending therefrom upon which handle a clip 13 is mounted to receive a supply package 14 of floss. This supply package will have a hole 15 preferably in its side from which a length of floss 16 may be drawn. The clip 13 is resilient so that when one supply package is exhausted, another may be substituted therefor by forcing the package 14 out of the clip and snapping a new supply package thereinto.

At the opposite end of the body 10 a fixed arm 17 extends generally at right angles to the extent of the body portion 10, and upon this fixed arm some suitable clamping device is mounted. The clamp which I have illustrated consists of a

post 18 grooved as at 19 for the reception of a strand of dental floss wound therearound. The post is formed in two sections consisting of a fixed section 20 and a shorter loose section 21 mounted 5 upon a pin 22.

At a point on the body between the end arm 17 and the supply package I mount a second arm 24 (illustrated in perspective in Fig. 5) by pivoting the curved end reduced portion of ear 25 of 10 this arm in the reduced curved recess 26 of body 10 to receive it, there being a hollow rivet 27 extending through the ear for such pivotal mounting, or the same may be detachably pivotally mounted for cleaning when desired. This arm 15 also carries a securing means similar to the securing means previously described; that is, a post 28 extends outwardly from the arm which is provided with a groove 29 for the reception of the dental floss. This post is formed in two sections 20 consisting of a fixed section 30 and a movable shorter section 31 slidably mounted upon the pin 32. This arm 24 may be rocked about its pivot 27 by a handle 33 extending from the arm generally longitudinally of the device. This handle 25 is arched upwardly as at 34 to provide a recess 35 into which the lip may extend, as at 36, to provide a guard (see Fig. 8), whereby the lip is prevented from interfering with the action of the device and will move with the device in operation. 30 I consider the term "lip" sufficiently broad to include any part of the face about the mouth which may come in contact with the holder. The body 10 being arched as at 11 receives the opposite lip 36' about the mouth so that the mouth 35 is not held open an undue extent when the side teeth are being cleaned. In this case, the side of the body of the device as seen in Fig. 8 will engage the lip at the corner of the mouth and hold the same back sufficient to enable the teeth on the 40 side to be viewed. The end of guard 37 also assists in this function. This arm 24 is provided with a guard plate 37 which will engage the lips 38 (see Fig. 6) or 39 (see Fig. 7) and will prevent this lip from crowding in about the device to 45 either be pinched by the device in the operation thereof or to prevent viewing of the portion being cleaned. This guard plate 37 tapers to a lesser width toward the handle 33 for better accommodation of the lip in the recess 35 when the arm 17 50 is placed in the mouth with the opposite end outwardly in the normal manner of use.

There is mounted on the guard plate 37 a cutting device 40 adjacent to the path of the dental floss. To thread up the dental floss a length is 55 drawn from the supply package and with the arm 24 swung forward, the floss is caused to follow the path shown at 49 to extend between the slit 41 formed between the sections of the post 28 and section 31, thence once about both sections 60 of the post to bind the portion extended in the slit therein, thence through the slot 42 in the guard plate, thence under the portion of the guard plate 43, and then upwardly through a slit 44 and past the cutter 40, thence to the post 18 65 in the groove 19 and about the sections thereof, thence through the slit 45 formed between the sections to lock the floss on the post. The fixed portion of the posts 18 and 28 are higher than the movable sections so as to form a guide for the insertion of the dental floss which is to be clamped by the post. The handle 33 may then be pressed to swing the arm about its pivot 27 and tension the floss in the area 46 between the arms. 70

The body is usually formed of some plastic and 75 there is some springiness in the body which regu-

lates to some extent the tautness of the floss by the tension applied. The arch of the body 11 also forms a stop to limit the amount of swinging action which the pivoted arm may have with its engagement with the arched portion 34. 5

When it is desired to renew the section of floss, the end 47 may be engaged and unwound from the post 18 and the used part may be severed close to the used section to avoid waste merely by pulling outwardly on the same against the 10 cutter 40. The floss extending between the cutter and wrapped about the post 28 may be left there until a new strip is desired when the portion of the floss beneath the portion of the plate 43 may be engaged for sliding the same out of the 15 slots 44 and 42 to be detached from the post 28 and a new length drawn out of the supply package and wrapped into clamped position around both posts as previously described. In some cases, the pivoted arm 24 need not be provided and a 20 fixed relationship embodying all of the other features except the tightening of the floss by reason of pivoted parts is as illustrated in Fig. 9. Here the fixed arm is designated as 50 instead of 24.

From the above, it will be apparent that when 25 the device is in use, the lip will be held back, giving greater visibility to the area being cleaned. It will be unnecessary for the operator to put his hand in the mouth in order to hold the lip back or to even use a second hand; and at the same time, 30 the lip will be prevented from being pinched.

The device is easily cleansed by merely holding the thumb over the hole 15 in the supply package and rinsing the same. The device may be hung 35 up on a hook by reason of the undercut fixed arm 17.

The foregoing description is directed solely towards the construction illustrated, but I desire it to be understood that I reserve the privilege of resorting to all the mechanical changes to 40 which the device is susceptible.

I claim:

1. A dental floss holder comprising a body with a pair of spaced arms extending therefrom, means on each arm to secure dental floss thereto to 45 span the space between said arms, one of said arms being located on said body at a position intended to be outwardly of the teeth to be cleaned during cleaning of the same and provided with lateral flanges extending oppositely therefrom 50 to provide a guard to engage and press back the lip out of the path of movement of the floss when manipulating the floss between the teeth.

2. A dental floss holder comprising a body with a pair of spaced arms extending therefrom, means on each arm to secure dental floss thereto to 55 span the space between said arms, one of said arms being located on said body at a position intended to be outwardly of the teeth to be cleaned during the cleaning of the same and provided with a recess therein of a depth inwardly beyond the line of direction of said floss to receive the lip and to provide an abutment to engage the surfaces of the lip to cause the same to move with the holder in the operation thereof. 60

3. A dental floss holder comprising a body with a pair of spaced arms extending therefrom, means on each arm to secure dental floss thereto to span the space between said arms, one of said arms being located on said body at a position intended 70 to be outwardly of the teeth to be cleaned during the cleaning of the same and provided with a laterally extending plate-like guard at right angles to the plane of the arms and of different lateral extents the wider portion being inwardly 75

and the narrower portion outwardly to engage and press back the lip out of the path of movement of the floss when manipulating the same between the teeth in the operation of the holder.

5. 4. A dental floss holder comprising a body with a pair of spaced arms extending therefrom, one of said arms being pivotally related to said body, means on each arm to secure dental floss thereto to span the space between said arms, lateral flanges on said pivoted arm extending laterally from said arm to engage and press back the lip out of the path of movement of the floss when manipulating the same between the teeth, and a handle on said pivoted arm manually engageable 10 to move the arm and guard thereon to tension the floss.

5. A dental floss holder comprising a body provided with a post having a fixed section and a movable section between which a strand of dental floss extends and is locked therebetween, by a portion 20 of said strand passing about said movable section and arranged to apply a binding action thereon, one of said sections being shorter than the other providing a surface to guide the strand 25 between the sections.

6. A dental floss holder comprising a body with a pair of spaced arms extending therefrom, means on each arm to secure dental floss thereto to span the space between said arms, one of said 30 arms being located on said body at a position intended to be outwardly of the teeth to be cleaned during cleaning of the same and provided with lateral flanges extending oppositely therefrom to provide a guard to engage and press back 35 the lip out of the path of movement of the floss when manipulating the floss between the teeth, and a cutter on said guard past which the floss extends in locating the same in operating position.

40. 7. A dental floss holder comprising a body with a pair of spaced arms extending therefrom, means on each arm to secure dental floss thereto to span the space between said arms, one of said arms being located on said body at a position intended 45 to be outwardly of the teeth to be cleaned during cleaning of the same and provided with

lateral flanges extending oppositely therefrom to provide a guard to engage and press back the lip out of the path of movement of the floss when manipulating the floss between the teeth, and slots extending inwardly from the edge of said guard for receiving the floss to locate the same in position on the holder. 5

8. A dental floss holder comprising a body with a pair of spaced arms extending therefrom, means on each arm to secure dental floss thereto to span the space between said arms, one of said arms being located on said body at a position intended to be outwardly of the teeth to be cleaned during cleaning of the same and provided with lateral flanges extending oppositely therefrom to provide a guard to engage and press back the lip out of the path of movement of the floss when manipulating the floss between the teeth, and slots extending inwardly from the edge of said guard for receiving the floss to locate the same in proper position on the holder, a cutter 20 on said guard located adjacent to the slot and on the side thereof nearest the other arm, whereby said slots after severing of the floss by the cutter 25 serve to hold the floss in a position for ready removal from said slots. 25

9. In combination a dental floss holder and a strand of dental floss comprising a body, a post on said body having a fixed section and a movable section, means for guiding the movable section for sliding movement on said guide toward and from the fixed section, said strand being wound about and extending between said sections as the sole means to hold said sections bound on said strand whereby the tension on the strand 30 performs the holding function of the same. 35

10. A dental floss holder comprising a body with a pair of spaced arms extending therefrom, one of said arms being a bell crank and pivotally related to said body, means on each arm to secure dental floss thereto to span the space between said arms, and the other portion of said bell crank providing a handle engageable to swing said pivoted arm and draw taut the dental floss which extends between said arms. 40 45
